FASTENING DEVICE

Leon Maroff Moghadam, Washington, D.C.; now by
change of name to Leo Markoff-Moghadam

Application January 14, 1955, Serial No. 481,868

5 Claims. (Cl. 24—113)

This invention relates to a fastening device and more particularly to a wire connector which is readily adaptable to a multiplicity of uses and is a continuation in part of application Serial Number 469,696 filed November 18, 1954, now Patent 2,715,486, granted August 16, 1955.

Heretofore, there have been numerous devices disclosed for the purpose of providing connectors for cords and wires of various sorts. There has not, however, been disclosed a fastening device possessing the simplicity of the presently-described invention nor does the prior art disclose a connector having the multiplicity of uses of the device herein disclosed. Prior art devices, for the most part, require a knotting or binding operation which requires a certain degree of manual dexterity and which may be unusually difficult when using cord of exceedingly small or very large diameter. Furthermore, generally speaking, such prior art devices must necessarily be provided in a great number of different sizes to accommodate cords and ropes of a variety of sizes.

The present invention provides a connector which is simple to utilize and which is of such a construction that a number of sizes of cords or wires may be used with a single connector size.

According to the present invention, a bent wire or a pair of wires is twisted to provide an intermediate loop and two spirally wound end portions. The end portions may be twisted so as to provide a tapering twist in which the loops are of a gradually-diminishing size, or the twisted end portions may consist of a plurality of groups of twists of different sizes, each group comprising a number of twists of the same size, or the twisted end portions may comprise twists of the same size. A cord may be passed through the enlarged central loop and pulled until it becomes engaged in one of the twisted end portions. The cord will be tightly retained in this position for, as the cord is pulled away from the connector, the end portion will be more tightly gripped by the twisted end portion of the connector.

One of the primary advantages of the present invention is its adaptability, for the presently-disclosed connector may be used with ribbon, string, rope, cord, wire, thread, or yarn. It is to be understood that in the following detailed description and claims the word "cord" as used is intended to cover any of the foregoing materials. By providing a variety of sizes of twists in the connector the same connector may be used with both very heavy cord and with fine thread.

A primary object of the present invention is to provide a fastening device which is extremely simple to operate and which will tightly retain the material with which it is used.

Another object of the present invention is to provide a connecting device made of wire which is readily adaptable to a multiplicity of uses.

Other objects and many of the attendant advantages of the present invention will be readily appreciated when considered in connection with the accompanying drawing wherein:

2

Fig. 1 is a plan view of one form of the present invention showing a pair of tapered twisted end portions with two threads engaged therewith,

Fig. 2 is a plan view of a second embodiment of the present invention having three groups of twists of different sizes, showing large cords engaged in the twisted portions,

Fig. 3 discloses still another embodiment having twists of the same size,

Fig. 4 is a side elevation of a fastening device designed for use as a shoelace connector, or as a belt fastener,

Fig. 5 is a plan view of a form of the invention designed for use in packaging,

Fig. 6 is an enlarged partial plan view of the connector shown in Fig. 5, and

Fig. 7 discloses a plan view of another form of the present invention.

Referring now specifically to Fig. 1, there is shown at 1 and 2 a pair of wires which are twisted together to provide an intermediate loop 3 and twisted end portions 4 and 5. The twisted end portions are so formed that the strands substantially contact one another and are resiliently biased towards each other. These strands however define a series of small substantially elliptical loops. In the embodiment shown in Fig. 1 the twists 6 immediately adjacent the intermediate loop are of the largest size and the twists constantly diminish in size to the smallest size adjacent the ends of the wires such as shown at 7. Accordingly the small substantially elliptical loops also diminish in size from the intermediate loop 3 to the ends of the strands. Cord is passed through the intermediate loop 3 and is pulled through the twisted end portions 4 or 5 so as to rotate the cord or the fastening device until the cord is tightly gripped within one of the small substantially elliptical loops formed by the twists. It can readily be seen that the point at which the cord will be gripped will depend upon the size of the cord, the larger sizes being retained by the twists 6 and the smaller sizes by the twists 7, and accordingly the small substantially elliptical loops formed by the twists are also of the same size.

Fig. 2 discloses a pair of wires 8 and 9 having twisted end portions. Each end portion in this embodiment is provided with groups of twists of three sizes. At 10 is shown a large twist, at 11 a twist of intermediate size and at 12 the smallest twist.

In Fig. 3 is shown a pair of wires 13 and 14 having twisted end portions 15 and 16. In this embodiment the twists are all of the same size.

In any of the embodiments shown in Figs. 1 to 3, the connector may be made of a single wire bent upon itself to form the intermediate loop and twisted end portions. When forming the connector of fine wire, it is unnecessary to provide any sort of securing means for the wire ends. However, when using large wires when using the device to connect large cables, it is possible that the wire ends be soldered or spot welded.

In Fig. 4 one type of connector is shown in which the wire 17 is provided with twisted end portions having twists of two sizes as shown at 18 and 19. The wire 17 is curved as shown so that it may be used to connect shoelaces. The connector fits snugly against the top of the shoe and the laces are secured in the twisted end portions. The use of a connector to secure shoelaces insures that the laces will be firmly retained in their tightened position and yet may be readily loosened, if desired, to adjust the degree of tightness. It is apparent that the embodiments of the invention disclosed in Figs. 1, 2 or 3 may be used as a connector for shoelaces. It is apparent also that a connector such as shown in Figs. 1 to 3 may be curved as required in a manner similar to that shown in Fig. 4 so that the connector may be

used with a belt, for example. The end portions of the belt may be provided with tabs or cards which are not shown, if necessary, to easily fit within the twisted end portions of the connector.

In Figs. 5 and 6 there is disclosed a fastening device designed specifically for the packaging art. Connectors 20 and 21 which are shown as being of the type disclosed in Fig. 3 are secured together with the twisted end portions of one connector extending outwardly at ninety degrees with respect to the end portions of the other connector. The connectors may be secured together in any suitable manner as by soldering or welding as shown at 22 in Fig. 6. It is apparent that, if desired, connectors of the type shown in Fig. 1 or 2 could be used in the manner shown in Fig. 5. Two cords or ribbons are used to tie a package and each end of a ribbon is passed through one of the twisted end portions. By use of this fastening device unskilled persons may tie up a package more quickly and more securely than was possible heretofore. It is apparent that large bows or other decorative devices may be secured on top of the connector so as to produce an artistic package.

In Fig. 7 there is shown a modified design of a connector which is useful specifically in connection with catches for jewelry and the like. An end portion of the connector is provided with an eyelet 23 to which one end of the bracelet or other jewelry may be permanently attached. The opposite end of the connector is provided with a protective head 24 which may be of plastic or other suitable material. It can be readily seen that the end of the jewelry is engaged in twisted end portion 24 to secure the jewelry in place. It is apparent that any of the modifications shown in Figs. 1 to 3 may be used in connection with this design. It is also possible to provide a protective head similar to that shown at 24 in place of eyelet 23.

In order to use a connector according to the present invention, the cord is passed through the enlarged central loop and portions of the cord are pulled through the twists of the end portion rotating the cord or connector until the cord is tightly engaged by a small substantially elliptical loop of the appropriate size. Cords of various sizes are shown in engaged position in Figs. 1 and 2.

The spring wedging effect increases with movement of the cord through the twists of decreasing radii. This increase in wedging effect is due to (1) the decrease in elasticity of the twists with smaller radii and (2) the decrease in the wedge angle which is caused by tension applied to the connector and the inseparable ends. This latter effect also serves to increase the wedging effect in connection with use of the connector having twists of the same size.

The presently-described invention has utility particularly where a secure quickly-detachable connection is desired. For example, with fishing tackle it is customary to attach the fish hook to the line by means of a leader and a detachable knot. When the line becomes wet and the knot tightens, it is difficult to loosen the knot to remove the hook. By using the fastening device herein described, it is possible to quickly secure or remove the hook leader from the line.

The invention also has particular utility wherever a line tightening means is required. For example, the present invention is well suited for use in connection with obtaining the correct degree of tautness for tent lines and with wires in the building industry. The presently-described connector also provides a detachable line tightener for clotheslines and the like.

The present invention may also be used wherever it is desirable to provide a means for relieving a certain portion of a line from tension. For example, when splicing electrical conductors it is desirable to provide some means to prevent the pulling of the splice. A connector accord-

ing to Figs. 1 to 3 may be applied to the line with the portions of the conductor adjacent each side of the splice secured in a twisted end portion of the connector.

Obviously many modifications and variations of the present invention are possible in the light of the above teachings.

What is claimed as new and desired to be secured by Letters Patent is:

1. A fastening device of the class described for clamping a cord or the like, comprising a plurality of wire strands interconnected at their ends and forming a relatively large elongated completely closed loop converging at least at one end in an end portion of a series of relatively small substantially elliptical loops, said end portion being comprised solely of twisted strands resiliently biased toward each other and at least the extreme end thereof being inseparable, and at least the first twist adjacent the large loop being sufficiently resilient to pass the cord, whereby a cord passed through the large loop may be drawn in between the strands of the end portion to be clampingly engaged by said strands.
2. A device as defined in claim 1 wherein the twists of said end portion are of constantly diminishing amplitude to provide clamping means for cords of varying diameter.
3. A device as defined in claim 1 wherein the twists of said end portion are formed of groups of twists, each group comprising twists of the same size, and the size of the twists of each group being progressively smaller in the direction of the extreme ends.
4. A fastening device of the class described for clamping a cord or the like, comprising a plurality of wire strands interconnected at their ends and forming a relatively large completely closed elongated loop converging at opposite ends in end portions each of a series of relatively small substantially elliptical loops, said end portions each being comprised solely of twisted strands resiliently biased toward each other, and at least the extreme end of each being inseparable, and at least the first twist adjacent the large loop being sufficiently resilient to pass the cord, whereby a cord passed through the large loop may be drawn in between the strands of an end portion to be clampingly engaged by the strands of said end portion.
5. A fastening device of the class described for clamping cords or the like, comprising pairs of wire strands each pair forming a relatively large completely closed elongated central loop and converging at opposite ends in end portions each of a series of relatively smaller substantially elliptical loops, said end portions each being comprised solely of twisted strands resiliently biased toward each other, and at least the extreme end of each being inseparable and at least the first twist adjacent the enlarged loop being sufficiently resilient to pass the cord, whereby a cord passed through the large loop may be drawn in between the strands of an end portion to be clampingly engaged by the strands of said end portion, said central loops being disposed at an angle with relation to one another and in overlying relationship and being secured to each other intermediate the twisted end portions.
